UNITED STATES PATENT OFFICE.

JAMES OLD, OF ALLEGHENY, PENNSYLVANIA.

STOP-VALVE.

SPECIFICATION forming part of Letters Patent No. 237,769, dated February 15, 1881.

Application filed October 20, 1880. (No model.)

To all whom it may concern:

Be it known that I, JAMES OLD, of Allegheny, in the county of Allegheny and State of Pennsylvania, have invented a new and 5 useful Improvement in Stop-Valves; and I do hereby declare that the following is a full, clear, and exact description thereof, reference being had to the accompanying drawings, and to the letters of reference marked thereon.

10 My invention relates to an improvement in stop-valves; and it consists in adjusting the valves with relation to their seat and holding them in an adjusted position for controlling the flow of the steam, gas, or liquids through 15 the openings in the valve-seats and chamber.

My invention also consists in the manner and means for suspending the valves in their chamber with relation to their seats, and for forcing and holding them to their seats, all of 20 which will hereinafter more fully appear.

To enable others skilled in the art with which my invention is most nearly connected to make and use it, I will proceed to describe its construction and operation.

25 In the accompanying drawings, which form part of my specification, Figure 1 is a vertical section of the valve-chamber and its valves when seated. Fig. 2 is a vertical section of the same when the valves are lifted off their seats.

30 Fig. 3 is a face view of the hanger on the lower end of the valve-stem. Fig. 4 is a face view of the valves on the side next to the hanger. Fig. 5 is a face view of the valves on the side next to their seats. Fig. 6 is a vertical 35 section of the hanger for the valves, representing said hanger when it is pivoted upon the valve-stem. Fig. 7 is a transverse section of the valves at line *y* of Fig. 4. Fig. 8 is a detail view of the levers, clevis, and valve-stem.

40 In the accompanying drawings, A represents the valve-chamber; B, its cap; C, its packing-box; D, the cap of the packing-box, and E the valve-stem, all of which are of ordinary construction.

45 On the lower end of the valve-stem E is pivoted a hanger, F, of peculiar construction, the form of which is clearly shown in Figs. 3, 4, 5, and 6, the hanger F in this case being pivoted to the valve-stem E and held in place 50 by means of a washer, *a*, and screw *b*; but I wish it clearly understood that I do not con-

fine myself to this construction and arrangement of the hanger, for it may be rigidly fixed upon the stem, or it and the stem may be constructed in one piece. 55

The valves G are recessed on one side, in which recess projects outward a section of a sphere, *c*, in the center of which is a recess, *d*. On the recessed side of the valves is a flange, *g*, projecting toward the center of the valve. 60 The under side of said flange forms a V-shaped recess, *e*, corresponding to the form of the ends *f* of the hanger F.

In the faces of the hanger F are circular concavities *h*, corresponding in contour to the 65 spherical projections *c* in the recessed side of the valves G, so that when said projections are placed in said concavities and the valves are suspended on the hanger F the plane of the outer face of the valves G may be inclined 70 in all directions, said projections *c* and concavities *h* forming a socket-joint, whereby such general inclination of the outer face of the valve may be had. In one of the concavities, *h*, is a projection, *i*, corresponding in outline to 75 that of the recess *d* in the spherical projections *c* of the valves G, which projection *i* and recess *d* may be used for suspending the valves G upon the hanger F.

It will be observed that by the recess *d* in 80 the spherical projection *c* the pressure on the valve in seating it is always distant from the center of the valve, which is a very apparent advantage as to leverage in holding the valve on and to its seat; and in the case of large 85 valves it becomes a very important feature as to leverage and economy of material in their construction.

The inward-projecting flange *g* and recess *e*, combined with the points *f* of the hanger, 90 is of great advantage in holding the valves G upon the hanger F while in the act of placing the valves in and removing them from between their seats and in placing them in and taking out of the valve-chambers A.

To the valve-chamber A is pivoted an upright arm, H, to the upper end of which is pivoted the operating-lever I, to which is pivoted the clevis J, connected to the valve-stem E. In the clevis J is pivoted a lever, K, having 100 an eccentric, *l*, which acts against the under side of the lever I, and thereby holds the stem

E and valve G in whatever position may be elected by the operator. The eccentric *l* acts as a wedge for wedging or holding the lever I in a fixed position, the operation of which with relation to the eccentric *l* and lever *k* will be readily understood by the skilled mechanic. Between the levers I and K is a spring, *m*, for causing a uniform pressure of the eccentric *l* against the lever I when the lever *k* is not held by the operator. The handle end of the lever K is placed in a slot in the lever I, as indicated in Figs. 1, 2, and 8, which arrangement of the levers enables the operator to manipulate both with one hand, the advantage of which will be apparent without further description.

The construction and arrangement of the several parts of my improvement in stop-valves will be readily understood from the foregoing description and by reference to the accompanying drawings.

The operation of opening and closing the valves consists in simply raising and lowering the lever I. By the construction and arrangement herein described of the valves and their hanger ease of construction, economy of material, application of pressure on the valves in holding them to their seats removed from their center toward their periphery, securely holding them on the hanger for placement and disappearance in their chamber, and adjustability of the plane of their face to the plane of the valve-seat is obtained, and the combination of a locking-lever with the operating-lever, the

operator can adjust and permanently fix the flow through the valve, all of which advantages are valuable, important, and desirable.

Having thus described my improvement, what I claim as of my invention is—

1. The combination of the levers I K, having an eccentric locking device, and the valve-stem, substantially as herein described, and for the purpose set forth.

2. The combination of the levers I K, having an eccentric locking device, clevis J, and valve-stem, substantially as hereinbefore described, and for the purpose set forth.

3. The combination of the levers I K, clevis J, spring *m*, and valve-stem, substantially as herein described, and for the purpose set forth.

4. The hanger F, with bevel-points *f* and cavities *h h*, in combination with the valves G G, having a recessed flanged, *g*, forming a section of a sphere recessed at its axis, substantially as herein described, and for the purpose set forth.

5. A valve having a V-shaped recess at or near its periphery, in combination with a hanger having a suspending-point corresponding in form to said V-shaped recess, substantially as herein described, and for the purpose set forth.

JAMES OLD.
